CLAIM

The ornamental design for a combined hamper and shelving unit, as shown and described.

DESCRIPTION

FIG. 1 is a front elevational view of a combined hamper and shelving unit showing my new design;

FIG. 2 is a rear elevational view thereof;

FIG. 3 is a side elevational view thereof;

FIG. 4 is a top plan view thereof;

FIG. 5 is a bottom plan view thereof;

FIG. 6 is a perspective view thereof.

The cross line shading which is partially shown is understood to represent conventional fabric and to repeat uniformly across the circumscribed area.
